GROVER CLEAVLAND BUSHONG, OF MARICOPA, CALIFORNIA.

TUBING-BLEEDER.

1,150,681.

Specification of Letters Patent. Patented Aug. 17, 1915.

Application filed April 20, 1915. Serial No. 22,581.

To all whom it may concern:

Be it known that I, GROVER CLEAVLAND BUSHONG, a citizen of the United States, and a resident of Maricopa, in the county of Kern and State of California, have invented certain new and useful Improvements in Tubing-Bleeders, of which the following is a specification.

My invention is an improvement in tubing 10 bleeders, and the invention has for its object to provide a device of the character specified, adapted for use in well casing, as for instance, oil wells, and the like, for permitting the tubing to be drained, of oil, water and the like, whenever desired, without the necessity of pulling the tubing from the well casing, wherein a detachable connection is provided between two adjacent tubing sections, capable of being operated from the 20 top of the well, and wherein a perforate barrel is connected with the lowermost of the said sections and slidably connected with the other of the said sections to permit the sections to be separated from each other 25 while yet connected by the barrel.

In the drawings, Figure 1 is a vertical section of an oil well, provided with the improved bleeder; Fig. 2 is an enlarged sectional detail of a portion of Fig. 1 showing 30 the parts in one position; Fig. 3 is a similar view showing the parts in another position; Fig. 4 is a perspective view of the upper section of the releasable mechanism; Fig. 5 is a similar view of the lower section; and Fig. 35 6 is a perspective view of the barrel.

The present embodiment of the invention is shown in connection with a well casing 1, in which is arranged a pump, the pump comprising a series of connected sections of tubing or tubular casing, arranged end to end and connected by unions 3. The lowermost section 4, and the preceding section 5 of the tubular casing have the bleeder connected therewith, and a pump cylinder 6 is connected with the lowermost section 4 at the lower end thereof. This pump cylinder is threaded at its upper end into the section 4, and a pump piston or plunger 7 of ordinary construction is arranged within the cylinder. The piston is connected to the sectional piston or plunger rod 8, by a spider connector 9, and the valve 10 of the piston

or plunger is arranged within the spider. The piston rod is sectional as shown, and the sections are connected by unions 11 in 55 the usual manner.

It will be evident that when the plunger or piston is reciprocated in the usual manner, the oil which fills the casing 1 will pass upward past the valve 10 into the casing 60 2-4-5 to the pump cylinder 6 and will gradually be raised to the top of the casing 2-4-5, to be finally discharged in the usual manner.

In pumps of this character, sand is very 65 liable to gain access to the casing 2-4-5, heaping up above the plunger, as indicated at 12, and in order to permit the oil and water above the sand to escape from the casing it must be pulled. When this occurs, the 70 weight of the oil above the sand is such that the casing of the pump is difficult to pull and the oil therein is wasted.

In the present invention mechanism is provided in connection with the casing for 75 permitting the oil and water above the sand to be drained from the casing. The casing sections 4 and 5 are connected by the collar 13 shown in Fig. 5. This collar, as shown at 14, is internally threaded at each end for 80 engaging the adjacent ends of the sections 4 and 5, and the said collar is also externally threaded as shown at 15, at its upper end. The lower end of the section 5 is externally threaded as shown at 16, to engage 85 the upper threads 14 of the collar, and the said section is also provided with an annular rib or collar 17 just above the threads, the said rib forming a stop for a purpose to be presently described. 90

A barrel 18 is arranged outside of the lower end of the section 5, the said barrel being internally threaded at its lower end, as indicated at 19, to engage the threads 15 of the collar 13. At its upper end the barrel 95 is provided with an internal annular flange or rib 20, for engaging the section 5.

The barrel is of such diameter that it will fit outside of the collar 13, and as a consequence an annular space is left between the 100 barrel and the exterior of the section 5. The flange or rib 20 is of such size that the interior thereof will fit the section 5 closely, as shown in Figs. 2 and 8, and will engage

the rib or stop 17, under conditions to be later set forth, to permit the barrel to connect the sections 4 and 5 when the section 5 is disengaged from the collar 13.

It will be noticed that the barrel is provided with a series of radial openings or perforations 21 for permitting the oil to pass freely from the barrel, and the barrel normally occupies the position shown in Fig. 2, that is, outside of the section 5. A sleeve 22 is arranged within the well casing 1 at the top of the cylinder 6, and the upper end of the bore of the said sleeve is reamed or beveled as indicated at 24.

15 A sleeve 25 is arranged on the section 4 intermediate the ends thereof, and the upper end of this sleeve is externally enlarged as indicated at 26, and the enlargement is beveled externally, to fit the reamed or beveled surface 24 of the sleeve 22. When the section 4 is lowered from the position shown in Fig. 1, to that shown in Figs. 2 and 3, this enlarged portion 26 of the sleeve 25 will engage the upper end of the sleeve 22 and 20 will seal the interior of the casing 1 between 25 said casing and the well tubing or casing.

The operation of the improved bleeder is as follows: When the sand indicated at 12 collects in the casing 2-4-5, and it is desired to bleed the same, the well pump casing 2-4-5 is lowered until the enlarged portion 26 of the sleeve 25 engages the beveled surface 23 of the sleeve 22, and seals the well casing as above described. A wrench 30 is now connected with the upper end of the pump casing 2-4-5, and the casing is turned in a direction to release the threads 16 of the section 5 from the threads 14 of the collar 13. As soon as the section 5 is 35 released from the collar 13, that portion of the pump casing above the collar 13 is lifted as shown in Fig. 3, and the oil within the pump casing above the collar 13 will drain out through the perforations 21 of the barrel, leaving only that small amount of oil 40 above the sand and below the collar 13. The oil runs out into the well casing 1 and is held in the casing, thus saving all of this oil usually wasted, and in addition greatly lessening the labor of pulling the casing, and the pump casing may be pulled from the well after the oil is drained. The stop 17 by 45 its engagement with the rib or stop 20 of the barrel limits the separating movement of the sections 4 and 5, and prevents their disengagement. After the oil has run out the section 5 may be re-connected with the collar 13, or the casing may be pulled with the parts in the position shown in Fig. 3. The 50 thread 14 at the top of the collar 13 is a left handed thread, as is also the thread 16 at the lower end of the section 5 of the pump tubing. The thread 13 at the top of the collar 13 is a right hand thread, as is also the 55 thread 19 of the barrel, and the thread 14 at

the bottom of the collar and inside the same. The engagement between the stops 17 and 20 is sufficient to permit the pulling of the pump casing and it is not necessary to reconnect the section 5 to the collar 13 for 70 pulling the casing.

The connection between the two sections 4 and 5 is a detachable connection, adapted to be operated from the top of the casing, and the barrel forms a slidable limiting and 75 perforate connection for permitting them to move away from each other within limits, to bring the perforate portion of the connection into operative position.

I claim:

1. In combination with a well casing and the pump casing therein and having a pump cylinder at the bottom and a plunger in the cylinder, of means in connection with the pump casing and the well casing and adjacent to the pump cylinder for sealing the space between the said casings when the pump casing is lowered with respect to the well casing, means in connection with the two lowermost sections of the pump casing 80 for bleeding the pump casing, and operable from the top of the pump casing, said means comprising a collar internally threaded at its upper and lower ends, the upper thread being a left hand thread, the two lower sections of the pump casing having a threaded engagement with the interior of the collar for connecting said sections, said collar being externally threaded at its upper end, and a barrel having its lower end threaded 85 to engage the external threads of the collar and having an internal annular flange at its upper end fitting the next upper casing section, said casing section having an annular stop for engaging the collar to limit the separating movement of the sections when the said last named section is disengaged from the collar, said barrel being perforated for 90 the purpose specified.

2. In combination with a well casing and the pump casing therein and having a pump cylinder at the bottom and a plunger for the cylinder, means in connection with the two lowermost sections of the pump casing for 95 bleeding the pump casing, and operable from the top of the pump casing, said means comprising a union into which the meeting ends of the sections are threaded, a perforate barrel connected with the union and extending upward around the next uppermost 100 section of the pump casing concentric with the same, and interengaging stops on the barrel and the said next upper section for permitting a limited movement of the barrel and the section with respect to each 105 other.

3. In combination with a well casing and the pump casing therein and having a pump cylinder at the bottom and a plunger for the cylinder, means in connection with the two 110

lowermost sections of the pump casing for bleeding the pump casing, and operable from the top of the pump casing, said means comprising a detachable connection between the two lowermost sections of the pump casing at their meeting ends and operable from the top of the casing, and a perforate bar-

rel connected with the lowermost pump section at the upper end thereof and outside of the next lowest section, and a slideable connection between the barrel and said last named section. 10

GROVER CLEAVLAND BUSHONG.
